HENNING BERNHARD MATHIAS PLEIJEL AND AXEL HERMAN OLSON, OF STOCKHOLM, SWEDEN, ASSIGNEES TO WESTERN ELECTRIC COMPANY, INCORPORATED, OF NEW YORK, N. Y., A CORPORATION OF NEW YORK.

MEANS AND METHOD FOR REDUCING CROSS TALK IN LOADING COILS.

Application filed May 5, 1921. Serial No. 467,035.

To all whom it may concern:

Be it known that we, HENNING BERNHARD MATHIAS PLEIJEL and AXEL HERMAN OLSON, subjects of the King of Sweden, residing at 5 Stockholm, Sweden, have invented certain new and useful Improvements in Means and Methods for Reducing Cross Talk in Loading Coils, of which the following is a full, clear, concise, and exact description.

10 This invention relates to means and methods for equalizing induction coils joined in pairs, the said induction coils serving in telephone cables to form a load of self induction on two main lines, and 15 simultaneously on the phantom lines formed thereof.

In the drawings, Figs. 1 to 3 are explanatory diagrams showing the relative directions of the magnetic fields caused by currents flowing in the various loading coil circuits; Figs. 4 and 5 show diagrammatically the testing circuits used in carrying out the equalization processes of the invention; Fig. 6 is a diagrammatic representation of the loading coil of the invention.

The arrangement of these pairs of coils is known per se from the English Patent No. 22,270 of 1914. In order also to obtain a sufficient load of self-induction for the 20 duplex line with pairs of coils of the said character, there must be provided connecting pieces of iron at the contact places of the duplex field between the one and the other coil of the pair, so as to reduce the 25 magnetic resistance. This arrangement is also known, the same having been described in the English Patent No. 22,133 of 1914. As the said connecting pieces have to be in direct contact with the cores of the coils, 30 the winding of the cores must be interrupted at the connecting places by a space equal to the width of the connecting pieces. It has been found that for this reason and by reason of the magnetic connection of 35 the cores of the coils by means of the connecting pieces, mutual inductive influences between the two coils are apt to cause cross talking in the said three circuits the said 40 inductive influences being due to small unsymmetries between the magnetic paths and also between the windings of the two coils.

The removal of these unsymmetries by

changing the position of the connecting pieces and of the windings has been found to be extremely difficult, if not impossible. 55 According to the invention, the pair of coils is therefore taken as it is when ready mounted, after which a compensation of the unsymmetries present is brought about only by a corresponding equalization of the 60 windings. The possibility of effecting this compensation by the windings only is due to certain conditions which are necessary and sufficient for the required non-inductivity, the said conditions having to 65 be fulfilled by the co-efficients of mutual induction between the windings of the coils, and also due to the equalizing windings arranged according to the invention so as to be capable of fulfilling the said conditions. 70

In the accompanying drawing, Fig. 1 represents two coils AB and A' B' of a pair of coils, the same being placed on top of each other although shown beside one another in the drawing. The connecting pieces are 75 assumed to be interposed between A and A' and between B and B'. The four halves of the windings are denoted by 1, 2, 3 and 4 their inductivities are L₁, L₂, L₃ and L₄. The positive direction of current flow 80 through the windings is that which in the respective halves of the coils creates a magnetic field having a direction indicated by the arrows. By a current creating a positively directed field in any of the halves 85 of the windings, there are produced, as shown by the arrows, positively directed magnetic fields in the two halves of the other coil, whereas a negatively directed field is produced in the second half of the 90 first coil. Thus the co-efficients of the mutual induction between the various halves of the windings are:

-M₁₂ M₁₃ M₁₄ M₂₃ M₂₄ and -M₃₄

95 Of these M₁₂ and M₃₄ each pertain to one of the two halves of the same coil, while the remaining four are for the connections between the separate halves of the adjacent coils.

100 Fig. 2 shows the directions of the fields belonging together in the case of main circuit currents flowing in two coils; Fig. 3 shows them as they are in duplex operation.

It is assumed that in main circuit operation, the currents in the lead and in the return, that is to say in 1 and 2 and in 3 and 4, equal each other with respect to the magnitude thereof, and that in duplex operation the currents are equally distributed on the two branches of the main conductors, so that currents of the same magnitude will flow through the windings 1, 2, 3 and 4.

10 By reason of symmetry, the first condition derived from the above is:

$$\begin{aligned} L_1 &= L_2, \\ L_3 &= L_4. \end{aligned}$$

15 In order that the two coils of the main lines shall not influence each other, the mutual induction of the one coil in main line connection on the other coil, which is connected in the same way, must be equal to 20 zero. By comparing Fig. 2 with Fig. 1, and assuming coil 3, 4, to be inducing, it is found that the inductions in the halves of the coil 1, 2, must then be equal but opposite. From this second condition is derived:

25 $M_{13} - M_{23} = M_{14} - M_{24}$.

The same condition will be deduced by assuming coil 1, 2, to be the inducing one.

If the main lines are not to influence the 30 duplex line, then the induction of each coil connected as a main circuit coil on each of the two halves of the other coil have to be equal to zero, the said halves forming branches of the duplex line. When coil 35 3, 4, is assumed to be an inducing main circuit coil, Fig. 2 gives the third condition:

$$M_{13} - M_{23} = M_{24} - M_{14}$$

and with coil 1, 2 as the inducing one, the 40 fourth condition

$$M_{13} - M_{14} = M_{24} - M_{23}$$

is arrived at.

Conditions 2 and 3 give together 45

$$\begin{aligned} M_{13} - M_{23} &= 0, \\ M_{24} - M_{14} &= 0. \end{aligned}$$

Conditions 2 and 4 give:

50 $\begin{aligned} M_{13} - M_{14} &= 0, \\ M_{24} - M_{23} &= 0. \end{aligned}$

From this the fifth condition

$$M_{13} = M_{14} = M_{23} = M_{24}$$

55 is obtained.

This means that the four-coefficients of mutual self-induction prevailing between the halves of the windings of adjacent coils must all equal one another. Conditions 1 60 and 5 thus represent the result obtained by the equalization.

Now, the method of equalizing is as follows:

According to Fig. 1, the equations

65 $M_{13} = M_{14}$ and $M_{23} = M_{24}$ of condition 5 are satisfied when the induction between coil 3, 4, in main line connection and each of the two winding halves of coil 1, 2, is equal to zero. If an alternating current for instance of a periodicity of 800 per second is 70 sent through the coil 3, 4, in main line connection, a telephone connected to the winding half 1 or 2 of the coil 1, 2, must be silent when the conditions are fulfilled. If it is not silent, which is mostly the case, an 75 equalization has to take place.

According to the invention, this is brought about by applying so many windings of the winding-halves which are being tested, or of the winding-half of the inducing coil 80 situated beneath the same, in common around these two halves of coils, until the telephone is silent. For instance, if the winding-half 1 is being tested, the equalization may be effected by winding a corresponding number of the windings previously wound only on to 1, around both 1 and 3. If the direction of winding around 3 is then the same as around 1, M_{13} will be reduced and M_{14} magnified. Conditions will be reversed when the direction of winding around 3 is opposed to the direction of winding around 1.

85 In the same manner, by commonly winding a suitable number of windings of half 2 around the halves 2 and 4, M_{23} will be equal to M_{24} . After the latter equalization the first one must be tested once more and, if necessary, be changed, so that both equalizations will at the same time fulfil the conditions made.

90 The next process of equalization has for its object to test condition 1, according to which L_1 has to be equal to L_2 , and L_3 equal to L_4 .

95 For this purpose each of the two coils are connected into a bridge, as shown in Fig. 4 for coil 1, 2. From the half having the larger self-inductivity, there are taken off as great a number of windings, and instead added to the half having the smaller self-inductivity, as will bring the contact C into the centre of the bridge wire. The equalization first described is not influenced by this latter equalization.

100 Now, the third equalization is still to be effected by which the claim $M_{13} = M_{24}$ of condition 5 is satisfied. If two circuits are formed from the four winding-halves, one of said circuits being formed by a series connection of the halves 1 and 3, while the second circuit is formed by connecting the halves 2 and 4 in series, the total inductivities of these two circuits will be

$$L_1 + L_3 + 2M_{13}$$

105 and

$$L_2 + L_4 + 2M_{24}.$$

110 On account of the preceding equalization,

these two inductivities equal one another, when $M_{18}=M_{24}$.

If now the pair of coils is connected into a bridge as indicated in Fig. 5 and the bridge is balanced, the contact C should be in the centre of the bridge wire if the mutual inductances M_{24} and M_{18} are equal to each other. If they are not equal to each other, the contact C will not be at the centre of the bridge wire, but will be located, for example, to the left of this centre, thereby indicating that for the particular pair of coils under test M_{24} does not equal M_{18} .

In order to obtain equivalence, an equal number of windings of each of the halves 15 and 4, are, according to the invention, wound simultaneously for instance around the half 1. By this procedure M_{18} and M_{14} are magnified by the same amount by which 20 M_{23} and M_{24} are reduced; thus the first equalization will not be changed, but it is in this way possible to bring C to the centre of the bridge wire, in order to make $M_{18}=M_{24}$, as required.

25 Thus, the equalization of the pair of coils is completed.

In order to simplify the equalization it is preferable to combine only such coils into pairs in which the two halves are already 30 made equal with respect to the inductivity, resistance and winding system. Then the second equalization procedure only comprises controlling and, if necessary, correction. The 35 equalization can then be commenced with the correction. It is, of course, immaterial which of the two coils is treated as the first one and which is treated as the second one, when the equalization is effected.

Fig. 6 shows schematically how the corrective windings above described are inserted on the two parallel cores of the loading coil. Windings 10 and 11 are the main line windings for the side circuit 12, 13 and 14 and 40 15 are the main line windings for the side circuit 16, 17. A few turns of main winding 10 are shown wound in common on core branches 18 and 19, and a few turns of main winding 11 are shown wound in common on core branches 20 and 21 for the purpose above 45 set forth in detail. A few turns of main line windings 14 and 15 are shown wound simultaneously around core branch 18 to further reduce cross talk between the three talking circuits. The two annular cores are suitably 50 connected by two connecting pieces of magnetic material 23 and 24.

Having now particularly described and ascertained the nature of our said invention and in what manner the same is to be performed, we declare that what we claim is:—

60 1. The method of reducing cross talk in a loading coil having a core of a plurality of branches for simultaneously loading a plurality of physical circuits and a derived

phantom circuit, which comprises removing a few turns of a main line winding found on one branch of the core and rewinding said turns in common around the last mentioned branch and a second of said branches.

65 2. The method of reducing cross talk in a loading coil having a core of a plurality of branches for simultaneously loading a plurality of physical circuits and a derived phantom circuit, which comprises removing a few turns of each of a plurality of main line windings found on different core branches and winding the removed turns simultaneously upon another branch of said core.

70 3. A magnetic structure of a plurality of branches for simultaneously loading a plurality of physical circuits and a derived phantom circuit comprising a main line winding on one of said branches for each line of each physical circuit and means comprising 75 windings wound in common on a plurality of said branches for reducing cross talk between said circuits.

75 4. A loading coil structure for simultaneously loading a plurality of physical circuits and a derived phantom circuit, comprising two annular cores of magnetic material, main line windings on said cores, and an auxiliary winding wound in common on portions of both of said cores for reducing 80 cross talk between said circuit.

85 5. A loading coil structure for simultaneously loading a plurality of physical circuits and a derived phantom circuit, comprising two annular cores of magnetic material, a main line winding on each half of each of said cores, and means comprising 90 winding wound around both of said cores in common for reducing cross talk between 95 said circuits.

100 6. The method of reducing cross talk in a loading coil for simultaneously loading a plurality of physical circuits and a derived phantom circuit, said coil having a core of a plurality of branches, said core having 105 on separate branches at least two main windings for each physical circuit, which method comprises equalizing the coefficients of mutual induction between the main windings by winding a small number of turns of 110 one main winding around a different branch of the core, and winding an equal number of turns from each of the two mentioned main windings of one physical circuit around a branch of the core surrounded by a main 115 winding of another physical circuit.

120 7. A magnetic structure of a plurality of branches for simultaneously loading a plurality of physical circuits and a derived phantom circuit comprising at least two main windings for each physical circuit located on different branches of said structure, an auxiliary winding of a small number of 125

turns connected in circuit with one main winding of one physical circuit and mounted on a branch of said structure surrounded by a main winding of another physical circuit, and a second auxiliary winding of a small number of turns connected in circuit with the second main winding of said one physical circuit and mounted on the same branch of said structure as said first auxiliary winding.

In witness whereof, we hereunto subscribe our names this 5th day of April, A. D., 1921.

HENNING BERNHARD MATHIAS PLEIJEL.
AXEL HERMAN OLSON.
